CLAIM

The ornamental design for a device mount for scanner, as shown and described.

DESCRIPTION

FIG. 1 is a top-rear perspective view of a device mount for scanner showing our new design;

FIG. 2 is a bottom-front perspective view thereof;

FIG. 3 is a rear end elevation thereof;

FIG. 4 is a front end elevation thereof;

FIG. 5 is a left side elevation thereof;

FIG. 6 is a right side elevation thereof;

FIG. 7 is a top plan view thereof;

FIG. 8 is a bottom plan view thereof;

FIG. 9 is a top-rear perspective view of a second embodiment of the device mount for scanner showing our new design;

FIG. 10 is a bottom-front perspective view thereof;

FIG. 11 is a rear end elevation thereof;

FIG. 12 is a front end elevation thereof;

FIG. 13 is a left side elevation thereof;

FIG. 14 is a right side elevation thereof;

FIG. 15 is a top plan view thereof; and,

FIG. 16 is a bottom plan view thereof.

The broken lines shown in FIGS. 1-16 represent environmental structure or portions of the device mount for scanner that form no part of the claimed design.
